UNITED STATES PATENT OFFICE.

CHARLES W. PEELLE, OF NEW YORK, N. Y., ASSIGNOR TO THE PEELLE COMPANY, OF BROOKLYN, NEW YORK, A CORPORATION OF NEW YORK.

CONTROLLING MECHANISM FOR ELEVATOR-CARS.

1,356,998.

Specification of Letters Patent. Patented Oct. 26, 1920.

Application filed July 5, 1918. Serial No. 243,434.

To all whom it may concern:

Be it known that I, CHARLES W. PEELLE, a citizen of the United States, residing at Hollis, in the borough of Queens, city of New York, county of Queens, and State of New York, have invented certain new and useful Improvements in Controlling Mechanisms for Elevator-Cars, of which the following is a specification, reference being 5 had therein to the accompanying drawings, which form a part thereof.

My invention relates to controlling mechanisms for elevator cars, and more particularly to a mechanism actuated by the movement of any door in a shaft, to prevent application of power to a car except when all of the doors in a shaft are closed.

Heretofore there has been devised and used, a controlling mechanism for elevator cars embodying an electric make and break mechanism operatively connected with all of the doors in a shaft, said mechanism either being arranged in a circuit to the controller upon the car, or in a circuit to a solenoid, 20 the actuation of which controls a clutch mechanism acting upon a shipper cable. The type of mechanism above referred to, necessitates the employment of an electric circuit, while in some elevator installations such a circuit is not available. Furthermore, it is sometimes undesirable to rely upon an electric circuit for preventing movement of a car while a door in the shaft is open.

It has been suggested, prior to the development of the electrical device above referred to, to use various devices operative upon the shipper cable upon mechanical or hydraulic elevator cars, but such devices 35 have not gone into extensive use. Electrical devices, however, are now, and have been extensively used.

A controlling mechanism made in accordance with my invention is designed particularly for use with mechanical or hydraulic elevators, wherein the motive power is controlled by a shipper cable, or other mechanical device, and wherein the installation does not include electrical devices, the current 45 to which may be utilized in a safety appliance for preventing movement of the car while a door is open.

In the practice of my invention, I provide a single controlling mechanism act-

ing upon the clutch controlling the shipper cable, and actuating means therefor, including therein a sliding weight operatively connected with all of the doors in a shaft. The construction and adjustment of this mechanism is such as to cause the clutch to be set 55 substantially simultaneously with the initial movement of any door in a shaft in opening same, and to release said clutch only when the door has been completely closed. The functionings of the controlling mechanism 60 are automatic throughout, and may not be tampered with in a manner to permit the actuation of the shipper cable except when all of the doors in a shaft are fully closed. 65

A controlling mechanism, made the subject matter of my invention, is supplemental to the ordinary lock on the doors, constituting what is generally known in the trade as a mechanical interlock, to afford a proper 70 safeguard against the actuation of any door in the shaft, except when a car is at the opening closed by that door.

While the sliding weight is operatively connected with all of the doors in a shaft, 75 the connection between said weight and each door must, of necessity, be such as to permit the opening and closing of any door in a shaft, without disturbing or affecting any other door in said shaft.

Said actuating means is so constructed and arranged as to be capable of use with any type of door, whether of the vertically sliding, laterally sliding, or hinge type, and it may be as readily applied to a vertically 80 sliding door of the truckable type, or of the telescoping type, the operation of the controlling mechanism being substantially identical, irrespective of the type of door to which it is applied. 85

The main object of the invention is to provide a controlling mechanism of the type to which my invention relates, wherein the shipper cable, or other means for controlling the power for the car, will be made inoperative by a single controlling mechanism, 90 purely mechanical in all of its functions, common to all of the doors in a shaft, and so constructed and arranged that the opening of any door will prevent the actuation of said shipper cable, or other device, and so maintain it until the opened door has again 95 been closed to an extent to cause the lock 100 105

upon the door to operate before power can be applied to the car.

The invention consists in such novel features of construction and combination of parts as are hereinafter set forth and described, and more particularly pointed out in the claims hereto appended.

Referring to the drawings,

Figure 1 is a fragmentary portion of an elevator shaft showing two doors of the truckable type, and having a controlling mechanism made in accordance with my invention, applied thereto;

Fig. 2 is a detail view upon a larger scale, of the portion of the controlling mechanism operative upon the clutch;

Fig. 3 is a section on line 3—3 of Fig. 2;

Fig. 4 is a view of a portion of an elevator shaft having therein doors of the telescoping type, with my invention applied thereto;

Fig. 5 is a similar view showing the invention applied to laterally sliding doors, and

Figs. 6 and 7 are, respectively, a view of a portion of an elevator shaft showing double swinging doors and a cross-sectional view thereof on a larger scale, a controlling mechanism made in accordance with my invention being shown in connection therewith.

Like letters refer to like parts throughout the several views.

In Fig. 1 of the drawings, I have shown an embodiment of the invention as applied to a type of door known as a truckable door, consisting of two door sections, *a* and *b*, arranged at each door opening in the elevator shaft, said sections moving vertically in the same plane, but in opposite directions, when opening and closing the door. The said sections are provided with a suitable lock *c*, operative when the doors are in the closed position. The two sections are connected by means of suitably mounted cables *d*, insuring their simultaneous movement.

The section *b* is provided with a laterally extending hanger bar *b'*, to which the cables *d* are connected. The doors *a* and *b* are mounted upon suitable rails or guides in the usual and well known manner.

Ordinarily a series of such doors are mounted in an elevator shaft, the door openings being positioned one above the other, so that the various hanger bars *b'* are all in the same vertical plane and extend parallel with each other. This general construction is old and well known in this art, and merely exemplifies one type of door in connection with which my invention may be employed.

In the type of elevator installation shown in the accompanying drawings, the power for actuating the elevator car, which car is indicated at *E*, is controlled by a shipper

cable *e* extending vertically of the shaft, passing over a pulley *e'* ordinarily arranged at the top of the shaft. Adjacent the pulley *e'* is a sleeve *f*, through which the shipper cable passes, said cable having two blocks, *e*² and *e*³, mounted thereon, the dimensions of which are such as to permit them to normally pass through said sleeve. This sleeve forms a part of a clutch mechanism for preventing movement of the shipper cable, the other and movable member of this clutch mechanism being a slide *f'* adapted to be projected within the sleeve in a position between the blocks *e*² and *e*³ so as to prevent their passage through said sleeve. This construction is old and well known in this art, it having been a common practice heretofore to actuate the movable clutch member by means of a solenoid, which solenoid is energized and deenergized by a mechanism controlling the circuit to the solenoid, to make said movable member operative, or inoperative. This mechanism was actuated by the movement of any elevator door in a shaft.

A slide *f'* is mounted in the fitting *f*² supporting the sleeve *f* and is acted upon by a spring *f*³ having a normal tendency to thrust the slide *f'* within the sleeve *f*.

Mounted upon suitable guide rails *g*, adjacent the sleeve *f*, is a sliding weight *h* operatively connected with each door in the elevator shaft, by means of the strip or cable *i*, passing through an opening in, and carrying blocks *i'* engaging the hanger bar *b'* of each door in a shaft.

To insure the desired movement of the strip or cable *i*, I provide the lower end thereof with a weight *j* which will always hold said strip or cable taut, but being of insufficient weight to overbalance the weight *h*.

At the bottom of the tracks or guides *g*, is a base plate *g'* supporting the actuating means for the slide *f'*, whereby said slide will be withdrawn from within the sleeve *f* when all of the doors in a shaft are closed. This means comprises a rocking lever *k* mounted upon the plate *g'* and connected by the slot and pin connection *k'* with the slide *f'*. Also mounted upon the plate *g'* is a bracket *m* having pivotally mounted thereon, a suitably formed lever, one arm *n* of which is arranged in the path of movement of the weight *h*, and the other arm *o* of which is adapted to operatively engage the rocking lever *k*. The design of the lever *k* may be varied to secure the desired quantity of, and timing, in the movement of the slide *f'*.

By this mechanism the spring *f*³ is utilized not only to actuate the slide *f'*, but also to set the actuating means for withdrawing said slide from within the sleeve, in a manner to cause the movement of the weight to be oper-

ative thereon, as well as upon the slide, when any door which has been opened, is closed.

In the form of the invention shown in Fig. 4, I have illustrated the invention as applied to a door structure of the telescoping, counterweighted type, in which the two door sections, a^2 and b^2 , have movement in parallel vertical planes and in the same direction, the opening and closing of the doors being facilitated by the counterweight p . In this form of the invention, the blocks i' upon the strip i , instead of operatively engaging a hanger bar upon the doors, engage an extension p' upon the counterweight p . In other respects the construction of the controlling mechanism is the same as shown in Figs. 1 to 3.

In the form of the invention shown in Fig. 5, I have illustrated the application of the invention to an elevator door of the laterally sliding type, this requiring merely the modification of the details in connecting the weight h with the door.

In this form of the invention, I connect the strip or cable i with an endless strip q passing around suitable rollers r , r' , r^2 and r^3 , arranged in pairs at the top and at the bottom of the elevator shaft. Extending from, and secured to, the reach q' of said endless strip q , are branch strips q^2 , extending about rollers s and s' at opposite sides of each door opening, to the reach q^3 upon the other side of the door openings, to which they are secured. Said branch strip or cable passes through an opening in a bracket t carried by the door proper u , having a free sliding fit in said bracket, and is provided with a block v adapted to engage said bracket.

Referring now to the form of the invention shown in Figs. 6 and 7, I have shown the invention as applied to double swinging elevator doors, this form of the invention like that shown in Fig. 5, requiring merely the modification of the connection between the weight h and the several doors in the shaft.

In this form of the invention, I employ a strip q having the same general arrangement as illustrated in connection with Fig. 5, this strip being endless and passing about rollers r , r' , r^2 and r^3 . The reach q^3 is provided with blocks w^4 adapted to be engaged by rings w^3 carried by extension strips or cables w passing over the rollers w' , adjacent the door opening, and the roller w^2 carried by one of the swinging doors w , and being connected with the other swinging door w' of the pair. By this construction it is impossible to open either swinging door section at any door opening, without moving the weight h in a manner to permit the spring f^3 to project the slide f' within the sleeve f in a manner to prevent movement

of the shipper cable e to an extent to apply power to the car.

In Figs. 5 to 7, the clutch mechanism, and parts appurtenant thereto, are not illustrated, the forms of the invention shown in said views relating merely to the manner of applying power to the weight h , and not involving any mechanical variation in the mechanism omitted from said views.

The operation of the herein described device is substantially as follows:—

Referring more particularly to the form of the invention shown in Figs. 1 to 3 of the drawings, when all of the doors in an elevator shaft are closed, the weight h will, through the connecting strip or cable i , hold each of the blocks i' upon said strip or cable, in engagement with its associated hanger bar b' of each door in the shaft. The load of the weight h is applied to the arm n of the lever acting upon the rocking lever k , in a manner to oscillate said lever k in the manner indicated in dotted lines, Fig. 3, and thus withdraw the slide f' from within the sleeve f , and present an unobstructed passage for the blocks e^2 and e^3 , through said sleeve. Under this condition, the shipper cable e may be actuated in either direction to apply power to the car.

When a car stops at any floor in a shaft, however, and the operator opens the door, as the section a moves upwardly, the section b moves downwardly, and the hanger bar b' thereon, through its engagement with the block i' associated therewith, raises the movable member or weight h through the connecting strip or cable i carrying said block. With the ascent of said weight h , the spring f^3 will project the slide f' within the sleeve f , and since when a car is brought to rest, the blocks e^2 and e^3 will be positioned beyond opposite ends of the sleeve f , said slide will be interposed between said blocks in a manner to prevent such subsequent movement of the cable e as will apply power to the car. This movement of the slide f' under the control of this spring f^3 , will rock the lever k , and through said lever, the lever $n-o$, in a manner to set the actuating mechanism for said slide preparatory to the descent of the weight.

The weight i is used in part as a counterweight to the weight h , and in part to hold the strip or cable i taut, so that with the opening of one door, the blocks i' associated with the hanger bars of all other doors in a shaft, will move away from their associated hanger bars, and thus avoid the possibility of the fouling of said strip or cable.

Before the operator may apply power to the car, it is necessary to first close any open door, the closing movement of the door permitting the weight h to descend and causing the block i' associated with the hanger bar of the door being closed, to follow the hanger

bar until the door is completely closed. When the door has been practically closed, each of the blocks i' will be in the operative relation to its associated hanger bar.

5 As the weight h approaches the limit of its downward movement, it engages the lever arm n , thus causing the other arm o of this lever to rock the lever k in a manner to retract the slide f' against the tension of the 70 spring f^3 , and thus withdraw said slide from within the sleeve f and permit movement of the shipper cable e .

10 The pin and slot connection k' between the lever k and the slide f' permits the operation above described.

15 Referring now to the form of the invention shown in Fig. 4, the operation is identical with that heretofore described in connection with Figs. 1 to 3, the sole difference being that the weight h is actuated through 20 the strip or cable i by the descent of the counterweight p instead of by the descent of the door itself.

25 The actuation of the slide f' , and the actuation mechanism therefor, in the form of the invention shown in Fig. 5, is identical with that heretofore described, this form of the invention differing from the form shown in Figs. 1 to 3 merely in the manner of actuating the weight h through the strip or cable i . When the door u is moved to the 30 right in opening the door, the bracket t will exert a thrust upon the block v , which, through the branch strip or cable q^2 , will move the endless strip or cable q about the various pulleys r', r^2 and r^3 . This movement of the strip or cable q will, through the strip or cable i , raise the weight. The 35 movement of the endless strip or cable q will result from the pull thereon from the branch strip or cable q^2 , thus causing an upward movement of the reach q' and a downward movement of the reach q^3 . During this movement the blocks v associated with other 40 doors in the shaft, will move away from their coöperating brackets t .

45 Upon the closing of the door the weight h will impart such travel to the endless strip or cable q as to cause the block v of the open door to follow the door in its closing movement, and the blocks v upon other doors to resume their normal position in close juxtaposition to their coöperating brackets.

50 The operation of the form of the invention shown in Figs. 6 and 7, differs from that of the form shown in Fig. 5 merely in the manner in which the door applies the actuating power to the strip or cable i .

55 In this form of the invention, if either door α or α' be open, it will exert a pull upon the strip or cable w which, through the ring w^3 , will impart travel to the endless strip or cable q in a manner to raise the weight h . This results from the passing of the extension strip or cable w about the pulley w^2

upon one door and attaching the end thereof to the other door. With this construction it is impossible to move either door without exerting a pull upon said strip or cable w , and hence neither door can be opened without developing conditions preventing the application of power to the car. When the doors are open, the parts will be in the position indicated by the dotted lines in Fig. 7.

70 When any door in the shaft is opened, the several blocks w^4 upon the endless strip or cable q associated with other doors, will move away from the ring w^3 of the branch strip or cable w of that door.

75 As the door is closed, the stresses upon the endless strip or cable q will be relieved, thus permitting the weight h to descend and actuate the clutch mechanism in a manner to permit the application of power to the car. This closing movement of the doors, 80 will create slack in the extension strip or cable w , which slack will be taken up by the movement of the endless strip or cable q during the movement thereof, imparted thereto by the weight h and the connection i .

85 It will be observed that in a controlling mechanism made in accordance with my invention, the device for preventing the actuation of the shipper cable, or other similar device, to apply power to the car, is purely mechanical throughout, and consists of a single mechanism operatively connected with each door in a shaft. In this manner the 90 installation of the elevator door equipment is very much simplified, and the clutch mechanism controlling the shipper cable, may be so positioned as to be inaccessible to the operator of the car, thus lending an additional factor of security in the elevator equipment.

95 The actuating means for the movable member of the clutch mechanism, being controlled entirely by the movement of the doors, may be so set as to avoid any possibility of the application of power to the 100 car except when all doors in a shaft are closed. While the strip or cable i may be accessible to the car operator, it will be observed that it cannot be used by the operator to release the shipper cable in a manner to permit application of power to the car, so long as any door is open, since its movement, resulting in the withdrawal of the slide, is not possible except with a closing movement of the door.

105 It is apparent that a controlling mechanism made in accordance with my invention is not only capable of application to various types of elevator doors, but may be readily applied to different types of doors in the same elevator shaft.

110 It is not my intention to limit the invention to the precise details of construction shown in the accompanying drawings, it being apparent that such may be varied with-

out departing from the spirit and scope of the invention.

Having described the invention what I claim as new, and desire to have protected 5 by Letters Patent, is:—

1. A controlling mechanism for elevator cars embodying therein a cable controlling the application of power to a car, having two adjacent blocks thereon, a sleeve 10 through which said cable and said blocks are adapted to pass, a slide adapted to enter said sleeve, a spring having a normal tendency to thrust said slide within said sleeve, a movable impact member, operative connections between said impact member and each door in an elevator shaft whereby said member will have movement coextensive with that of the opening and closing movement of the door, an oscillatory lever so positioned as to be engaged by said impact member substantially simultaneously with the limit of the full closing movement of any door, and to be disengaged thereby substantially simultaneously with the initial 25 opening movement of any door and operative connections between said lever and said slide, whereby said slide will be actuated by said spring to prevent movement of said cable when any door in a shaft is open, and 30 will be retracted to permit movement of said cable only when all doors in a shaft are closed, and said spring will normally maintain said lever in the operative relation to said impact member.

35 2. A controlling mechanism for elevator cars embodying therein a cable controlling the application of power to a car, having two adjacent blocks thereon, a sleeve through which said cable and said blocks are adapted to pass, a slide adapted to enter said sleeve, a spring having a normal tendency to thrust said slide within said sleeve, a movable impact member, operative connections between said impact member and each door in an elevator shaft, an oscillatory lever arranged in the path of movement of said impact member and adapted to be engaged thereby when all doors in a shaft are closed, and a lever adapted to be engaged by said first named lever and to operatively engage said slide, whereby said slide will be actuated by said spring to prevent movement of said cable when any door in a shaft is open, and will be retracted to 50 permit movement of said cable only when all doors in a shaft are closed, and said spring will normally maintain said lever in the operative relation to said impact member.

55 3. A controlling mechanism for elevator cars embodying therein a cable controlling the application of power to a car, having two adjacent blocks thereon, a sleeve through which said cable and said blocks are adapted 60 to pass, a slide adapted to enter said sleeve, a

spring having a normal tendency to thrust said slide within said sleeve, a movable impact member, operative connections between said impact member and each door in an elevator shaft, a compound lever system, the 70 first lever of which is arranged in the path of, and adapted to be engaged by, said impact member, when all doors in a shaft are closed, and the last lever of which acts upon said slide, whereby said slide will be actuated by said spring to prevent movement of said cable when any door in a shaft is open, and will be retracted to permit movement of said cable only when all doors in a shaft are closed, and said spring will normally 75 maintain said lever in the operative relation to said impact member.

4. A controlling mechanism for elevator cars embodying therein a cable controlling the application of power to a car, having two adjacent blocks thereon, a sleeve through 80 which said cable and said blocks are adapted to pass, a slide adapted to enter said sleeve, a spring having a normal tendency to thrust said slide within said sleeve, a vertically sliding weight, operative connections between said weight and each door in an elevator shaft, a compound lever system, the first lever of which is arranged in the path of, and adapted to be engaged by, said weight 85 when all doors in a shaft are closed, the last lever of which acts upon said slide, whereby said slide will be actuated by said spring to prevent movement of said cable when any door in a shaft is open, and will be retracted to 90 permit movement of said cable only when all doors in a shaft are closed, and said spring will normally maintain said lever in the operative relation to said impact member.

5. A controlling mechanism for elevator cars embodying therein a cable controlling the application of power to a car, having two adjacent blocks thereon, a sleeve through which said cable and said blocks are adapted to pass, a slide adapted to enter said sleeve, a spring having a normal tendency to thrust said slide within said sleeve, a vertically sliding weight, operative connections between said weight and each door in an elevator shaft, a rocking lever, one arm of which is operatively connected with said slide, and a second lever mounted adjacent the lowermost position of said weight, with one arm thereof projected in the path of movement thereof, and with the other arm thereof in 100 operative engagement with the other arm of said rocking lever, whereby the engagement of said weight with said last named lever will retract said slide and permit movement of said cable to apply power to a car 105 toward the completion of the movement of said weight, and the disengagement of said weight and said lever will permit said slide to be actuated by said spring to prevent movement of said cable substantially simul- 110

65 130

taneously with the initial opening movement of the door, said spring acting through said slide upon said lever to restore said lever to its normal operative relation to said weight, whereby said slide will be actuated by said spring to prevent movement of said cable when any door in a shaft is open, and will be retracted to permit movement of said cable only when all doors in a shaft are closed, and said spring will normally main-

tain said lever in the operative relation to said impact member.

In witness whereof I have hereunto affixed my signature, this 26th day of June, 1918, in the presence of two subscribing witnesses. 15

CHARLES W. PEELLE.
